JEWELRY DISPLAY TRAY

Samuel M. Rosen, 333 N. Michigan Ave.,
Chicago, Ill. 60601

Filed May 23, 1966, Ser. No. 2,387

Term of patent 14 years

(Cl. D80—9)

FIG. 1 is a view in perspective of a jewelry display tray showing my new design;

FIG. 2 is a side view in elevation thereof;

FIG. 3 is a front view in elevation thereof; and

FIG. 4 is a rear view in elevation thereof.

The drawing is shaded to depict the contrast between the trim line at the intersections of the sides and center panel, and the sides and center panel.

The broken line representation of a ring in FIGS. 1 and 2 is for purposes of illustration only.

I claim:

The ornamental design for a jewelry display tray, substantially as shown and described.
